Kevin Prince(57) **CLAIM**

The ornamental design for a brazed rebar gabion façade, as shown and described.

DESCRIPTION

FIG. 1 is a perspective view of a brazed rebar gabion façade, showing my new design;

FIG. 2 is an enlarged perspective view thereof;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2; and,

FIG. 8 is a bottom plan view of FIG. 2.

The broken lines showing rocks in FIG. 1 depict environmental matter and form no part of the claimed design. The remaining broken lines depict portions of the brazed rebar gabion façade that form no part of the design. The welds shown at intersections of vertical and horizontal rebar are shaded to depict a bright contrasting golden color when compared with the rebar that is depicted by darker shading.
